UNITED STATES PATENT OFFICE.

JOHN H. PRICE, OF NEAR MOUNT CORY, OHIO

WAGON-RACK.

SPECIFICATION forming part of Letters Patent No. 785,760, dated March 28, 1905.

Application filed December 13, 1904. Serial No. 236,719.

To all whom it may concern:

Be it known that I, JOHN H. PRICE, a citizen of the United States, residing near Mount Cory, in the county of Hancock and State of Ohio, 5 have invented a new and useful Wagon-Rack, of which the following is a specification.

This invention relates to that class of wagon-racks which are adapted to be converted so that they may be utilized for a variety of purposes—such as, for instance, for the purpose of hauling such material as baled hay or corn in the stalk, which requires a flat wagon-bed, for hauling loose hay, which requires an extended wagon-bed, for the purpose of hauling 15 grain or live stock, such as hogs, which requires a suitably-constructed box, or for other purposes.

The principal object of the invention is to simplify the construction and to improve the 20 operation of this class of devices; and with these and other ends in view, which will readily appear as the nature of the invention is better understood, the same consists in the improved construction and novel arrangement 25 and combination of parts, which will be hereinafter fully described, and particularly pointed out in the claims.

In the accompanying drawings has been 30 illustrated a simple and preferred form of embodiment of the invention, it being, however, understood that no limitation is necessarily made to the precise structural details therein exhibited, but that the right is reserved to any changes, alterations, and modifications to 35 which recourse may be had within the scope of the invention and without departing from the spirit or sacrificing the efficiency of the same.

In said drawings, Figure 1 is a perspective 40 view of a wagon-rack embodying the principles of the invention, the same being arranged for use as a stock-rack. Fig. 2 is a longitudinal sectional view. Fig. 3 is a transverse sectional view looking in a forward direction. 45 Fig. 4 is a transverse sectional view looking in a rearward direction. Fig. 5 is a horizontal sectional view taken on the line 5 5 in Fig. 3. Fig. 6 is a sectional detail view taken through the extremity of one of the bed-sup-

porting braces. Fig. 7 is a perspective detail view of a portion of one of the side members of the device, showing one of the arms or brackets connected therewith.

Corresponding parts in the several figures are indicated by like characters of reference.

The improved wagon-rack includes a pair of longitudinally-disposed sills 1 1, which are adapted to be supported upon the bolsters of the running-gear, one of which has been indicated at 2 in Fig. 4 of the drawings, said 50 bolsters being provided in the usual manner with standards 3 to support the said sills. The sills 1 1 serve to support a plurality of pairs of cross-braces 4 4, said cross-braces of each pair being suitably spaced apart, as will be 55 best seen by reference to Figs. 1 and 2 of the drawings. Said cross-braces are preferably gained into the upper edges of the sills, which latter are thereby spaced and connected. Each of the sills is, moreover, connected with 60 each pair of braces by means of obliquely-disposed clips 5 5, whereby the parts are firmly connected. The lower edge of each sill is provided with a recess 6, above which a rub-iron 65 7 is suitably secured. The flooring 8, which 70 constitutes the bed of the device, is suitably secured upon the transverse braces 5 5, the ends of which latter are suitably extended beyond the side edges of the bed.

Each of the cross-braces 5 is provided near 75 its extremities with bolts 9, extending vertically therethrough, for the purpose of preventing said braces from splitting under the strain to which they will be subjected. Each 80 pair of braces are also connected at the ends 85 thereof by means of horizontally-disposed bolts. 10.

The sides 11 of the rack are composed of planks, to the outer sides of which are secured arms or brackets 12, composed of pieces of 90 scantling of suitable dimensions, the inner sides of which contacting with the planks of which the side members are connected are beveled, as shown at 13, so that the lower ends of said brackets will extend downwardly 95 and outwardly from the side members 11. These brackets are made of such dimensions and are disposed in such a manner upon the

side members 11 that they will fit between the projecting ends of the pairs of cross-braces 4 4, the lower edges of the planks constituting the side members being adapted to rest upon 5 the bed or flooring adjacent to the side edges of the latter. The arms or brackets 12 are provided in their outer sides with transverse notches 14, adapted when the side members are tilted to the position indicated in Fig. 3 of 10 the drawings to engage the transverse bolts 10, connecting the ends of the cross-braces 4, whereby the side members will be partly supported in the extended position shown in 15 said figure. The lower ends of the arms 12 are cut off obliquely, as shown at 15, so that when the side members are extended the said lower ends of the arms or brackets will abut 20 squarely upon the outer sides of the sills 11, thus affording a great additional support of 25 the side members and enabling the latter to support heavy loads without the necessity of resorting to bolts or other fastening means 30 for the purpose of securing them temporarily in extended position.

When the side members 11 are elevated to the position shown in Fig. 1, they constitute the sides of a wagon-box, and when thus raised the inner sides of said side members are abutted upon the front and rear end-gates 16 and 17. Said front and rear end-gates are each provided with uprights 18, upon which the planks 19, constituting the end-gates proper, are horizontally secured. The uprights 18 of said end-gates are extended downwardly through the wagon-bed and between 35 the front and rear pairs of cross-braces, respectively, as will be clearly seen in Fig. 2 of the drawings. The side members 11 when raised to abut upon the end-gates may be connected by means of hook-bolts, as shown at 40 20, or by means of draw-bolts of ordinary construction.

The upper ends of the uprights 18 of the front end easing are connected by spaced 45 planks 21 for the convenient attachment of a booming-piece 22, which, as shown, consists of an iron pipe or rod bent to form a yoke, the arms of which are provided at their lower ends with offset portions forming shoulders 50 23, adapted to rest upon the upper edge of the end-gate proper, while the arms of the yoke rest against the sides of the spaced planks 21. The arms of the yoke are provided with eye-bolts 24, extending through perforations in 55 the uppermost plank 21 and provided with nuts 25, whereby the booming-piece is secured in position detachably. Said booming-piece may be secured either upon the outside or inside of the end-gate, as may be preferred, 60 and said booming-piece may be extended upwardly to any desired height. The arms or side members of the yoke constituting the booming-piece are connected by means of a clamp 26, the side members of which are con-

nected by means of a bolt 27, so as to permit 65 said clamp to be adjusted vertically upon the booming-piece. One end of said clamp 26 is extended vertically to form a hook 28, which is serviceable as a line-support.

When the side members are raised to constitute 70 a wagon-box, extension-racks 29 may be mounted thereupon, said extension-racks being composed of planks 30, connected by vertically-disposed braces 31, which are secured to opposite sides thereof and which are 75 extended downwardly, so as to engage the side members 11, as will be clearly seen in Figs. 1 and 4. Hooks 32 may be provided upon the end-gates to engage staples 33 upon the extension-racks for the purpose of securing 80 the latter in position.

From the foregoing description it will be seen that a wagon-rack has been provided which is capable of varied and extended use. When the side members are detached, a flat 85 wagon-bed is provided upon which material may be loaded between the end-gates, which are supported and strongly braced and reinforced by the uprights 18 being extended downwardly between the cross-braces supported upon the sills. When the side members 11 are placed in position, they may be folded up against the end-gates, so as to constitute a grain-box, or they may be folded down to the position shown in Fig. 3 to constitute 90 a hay-rack. When the device is used as a hay-rack, the booming-piece engages the front end of the pole or boom by which the load is secured. If the load is a small one, the pole may be secured under the adjustable 95 cross-brace 26, which latter may be adjusted at any desired elevation. Said booming-piece is readily detachable when its presence is not required. When the side members 11 are elevated to form a wagon-box, the extension-racks 100 may be used, transforming the device into a stock-rack. Thus it will be seen that the device may be readily utilized for a great variety of purposes by merely making slight changes in the relative disposition of the parts 105 thereof.

The improved device is simple in construction and may be manufactured at a moderate expense.

Having thus described the invention, what 115 is claimed is—

1. In a device of the class described, a pair of sills, a plurality of pairs of transverse braces supported upon said sills, the braces of each pair being suitably spaced apart, and obliquely-disposed clips connecting the braces with the sills. 120
2. In a device of the class described, a pair of sills, a plurality of pairs of cross-braces mortised in the said sills and spaced apart, and obliquely-disposed clips connecting each sill with each pair of braces. 125
3. In a device of the class described, a pair of

sills, a plurality of pairs of transverse braces supported upon and extending beyond the sills, the braces of each pair being spaced apart and connected by bolts near the ends

5 thereof, flooring constituting a bed supported upon said braces, and side members having arms extending downwardly between said braces.

4. In a device of the class described, a pair of
10 sills, pairs of braces supported transversely upon said sills, bolts connecting the braces of each pair near the ends thereof, flooring supported upon the braces, side members having arms or brackets extending downwardly and
15 outwardly, said brackets being provided with notches adapted to engage the connecting bolts at the ends of the braces and with oblique lower ends adapted to abut upon the sides of the sills.

20 5. In a wagon-rack, a pair of sills, pairs of braces supported transversely upon said sills, means for securing said braces upon the sills and against longitudinal movement upon the latter, and an end-gate having downwardly-extended vertical members adapted to engage between the pairs of braces.

6. In a wagon-rack, a pair of sills, a plurality of pairs of braces secured transversely upon said sills, flooring constituting a bed supported
30 upon said braces, and an end-gate having vertical members extending downwardly through the flooring and between the pair of braces, adjacent to the sills.

7. In a wagon-rack, a plurality of pairs of braces, a pair of sills supporting said braces, flooring supported upon said braces, side members having downwardly-extended brackets, bolts connecting the ends of the pairs of braces and adapted to support the brackets of the side
40 members, and end-gates having vertical members extended through the flooring and between pairs of braces.

8. In a wagon-rack, a plurality of pairs of braces, sills supporting the same, bolts extending vertically through said braces near the extremities thereof, horizontally-disposed bolts connecting the pairs of braces near the ends thereof, side members having brackets extending downwardly between the pairs of braces
45 and having notches adapted to engage the hori-

zontal connecting-bolts, said brackets having oblique lower ends, end-gates adapted to space the side members, and means for connecting said side members.

9. An end-gate having upright members 55 and spaced planks connecting the same, in combination with a boom-piece consisting of a yoke having shoulders or offsets engaging one of the spaced planks, and means for securing said boom-piece upon the end-gate. 60

10. In a device of the class described, the combination with an end-gate, of a booming-piece consisting of a yoke detachably connected with said end-gate and a clamp adjustably mounted upon and connecting the side members of said yoke. 65

11. In a device of the class described, the combination with an end-gate, of a booming-piece consisting of a yoke detachably connected with said end piece, and a clamp adjustably mounted upon and connecting the side members of said yoke, said clamp being extended at one end to form a hook constituting a line-support. 70

12. The combination with an end-gate, of a 75 booming-piece having an adjustable cross-brace.

13. The combination with an end-gate, of a booming-piece consisting of a yoke detachably connected with said end-gate, and a cross-brace vertically adjustable upon said yoke. 80

14. In a device of the class described, a pair of sills, a plurality of pairs of cross-braces supported upon said sills and having extended ends, bolts connecting said extended ends, a 85 flooring supported upon the sills, end-gates having vertical members extending through the flooring and between the cross-braces, side members having arms or brackets engaging between the pairs of braces and provided with 90 notches, means for connecting the side members in a raised position, and extension-racks detachably connected with said side members.

In testimony that I claim the foregoing as my own I have hereto affixed my signature in 95 the presence of two witnesses.

JOHN H. PRICE.
